CLAIM

The ornamental design for a mount for electronic devices, as shown and described.

DESCRIPTION

FIG. 1 is a top, front, and first-side perspective view of a mount for electronic devices embodying the new design; FIG. 2 is a top, back, and second-side perspective view thereof;

FIG. 3 is a back and second-side perspective view thereof; FIG. 4 is a bottom, front, and first-side perspective view thereof;

FIG. 5 is a top view thereof;

FIG. 6 is a bottom view thereof;

FIG. 7 is a first-side view thereof;

FIG. 8 is a second-side view thereof;

FIG. 9 is a front view thereof; and,

FIG. 10 is a back view thereof.

The uniform repeating broken lines depict portions of a mount for electronic devices in which the claimed design is embodied and form no part of the claimed design.

1 Claim, 10 Drawing Sheets
